ROTARY WELL DRILLING UNIT

John E. Brantly, Avenal, Calif., and John M. Shimer, Dallas, Tex., assignors to Oil Well Supply Company, Dallas, Tex., a corporation of New Jersey

Application November 13, 1936, Serial No. 110,726

6 Claims. (Cl. 255—19)

This invention relates to a rotary well drilling apparatus of the type used in drilling deep petroleum wells.

5 Rotary well drilling apparatus for drilling wells of this type comprises a power driven rotating horizontal table through which a vertical drill stem extends in such manner that it is engaged and rotated on its axis with the table, but may slide vertically, thus enabling it to descend as 10 the well becomes deeper and to be lifted for the insertion of additional lengths of drill stem. The power for rotating the table and for hoisting and lowering the drill stem has heretofore generally been transmitted from a common source of power 15 through a drawworks at the side of the derrick. This drawworks comprises a hoisting drum and change speed driving mechanisms for rotating it at selected speeds and also a sprocket from which a chain extends above the floor of the derrick 20 to the rotating table located at the center of the derrick.

This arrangement for driving the rotary table and the hoisting mechanism has a number of disadvantages among which are the space taken up 25 within the derrick by the sprocket chain and its guard extending from the drawworks to the rotary, the noise and wear of the rotary chain and the difficulty in setting the rotary in position to drill a "rat hole" to receive the grief 30 stem when the latter is hauled out of the well and disconnected from the hoisting apparatus. Moreover, a more powerful engine is required to operate the hoists than to rotate the rotary and although the rotary is operated for a greater portion 35 of the time than the hoists the engine for supplying the power must be large enough to operate the hoists. Therefore the engine is run inefficiently for a large part of the time during which it is driving only the rotary. The coupling 40 of the rotary and hoisting apparatus to a common source of power through the drawworks also renders the control of the drilling operations cumbersome because each operation of hoisting and rotary drilling is governed to some extent 45 by the requirements of the other.

These various disadvantages are obviated and avoided in our present invention in which the rotary is driven independently of the power for driving hoisting mechanisms or drawworks and 50 in which, therefore, a smaller power suited for driving the rotary efficiently may be employed.

Our present invention also has further advantages in making available this independent rotary operating power for operating the hoists 55 in case of emergencies and also in enabling the

rotary itself to be operated from the drawworks in case its own power should fail in an emergency.

The various features of the invention are illustrated by way of example in the accompanying drawings in which—

Fig. 1 is a plan view and Fig. 2 a vertical side elevation of a rotary table and the driving mechanism therefor, and Fig. 3 is a vertical sectional view of part of the apparatus shown in Figs. 1 and 2 and showing certain coupling mechanisms, 10 change speed mechanism and a part of the engine casing to which the latter is secured.

In our present invention the rotary table and an engine for driving it are mounted as a complete unit on a common base so that all of the 15 elements of the unit are in permanent, definite positions relative to each other and so that it may be moved into position and operated as a unit. Power is transmitted from the engine through a change speed mechanism which is 20 mounted on the engine or on the base of the engine and therefore in rigidly fixed position relative to the drive shaft of the latter. Power from the change speed mechanism is transmitted 25 through a coupling to a shaft driving the rotary. Also mounted on the rotary shaft with the coupling is a sprocket wheel through which the rotary may be driven from an outside source of power when the coupling is uncoupled. Mounted 30 on the shaft of the change speed mechanism adjacent the coupling is a sprocket wheel which may be employed for emergency driving of the hoists. The coupling may be of any suitable type, preferably a pair of sprocket wheels arranged coaxially on the adjacent ends of their 35 respective shafts and with closely adjacent faces so that when a chain is wrapped about these wheels with the links spanning the spaces between teeth of both wheels, the shafts on which these sprocket wheels are mounted are coupled 40 together.

Referring more particularly to Figs. 1 and 2 of the accompanying drawings, a reversible engine 45 and a drilling rotary 11 are mounted on a pair of parallel skids 12 and 13 which form a common base or support for the engine and rotary. The engine and rotary may, therefore, be handled as a unit. Power is transmitted from the engine 10 through a change speed mechanism 50 such as the two speed transmission 14 to a shaft 15 that carries a sprocket wheel 16 and a sprocket wheel 17 that acts as one element of a coupling. The other member of the coupling comprises a sprocket wheel 18 which is keyed 55

onto the drive shaft 19 of the rotary 11. A second sprocket 20 is also keyed on the shaft 19.

The construction of the two speed transmission and of the coupling and sprockets is shown more in detail in Fig. 3. As shown in this figure, the change speed mechanism 14 is enclosed in a casing 21 having flanges 22 through which it is open to the casing 24 of the engine 10. It is also provided with sidewise flanges 25 and 26 which are supported on and bolted to an extension of the engine frame 27. The change speed mechanism is thus readily connected with the engine casing.

The engine 10 has a drive shaft 28 that projects through the engine wall 29 into the transmission casing 14 and has keyed on it, within the casing, a gear 30. The shaft 28 is in alignment with the shaft 15, which extends through anti-friction bearing 31 in the opposite wall of the casing 14 and into an anti-friction bearing 32 mounted in a recess in the gear 30 which overhangs the end of the shaft 28. The end of the gear 30 nearest the shaft 15 is recessed and provided with a number of internal teeth 33 that may be engaged by teeth 34 on a clutch element 35 slidably aligned on an enlarged part of the shaft 15. The clutch element 35 may be moved into the recess in the gear 30 by means of a sliding arm 36 threaded onto the shaft 37 journalled in the upper part of the transmission casing 14, and actuated by a crank 38. In this position the teeth 33 and 34 intermesh and the shaft 15 is keyed directly through the clutch element 35 and the gear 30 to the drive shaft 28. In this position of the clutch 35, therefore, the shaft 15 is to be driven directly and at the same speed as the shaft 28. The two sprocket wheels 17 and 18 may be coupled together by means of a chain 39 having link pins 40 that span the two sprocket plates 17 and 18 and being positioned between the teeth of the sprockets serve to couple them together. This is the arrangement in which the rotary would be driven at low speed.

The gear 30 meshes with a smaller gear 41 on a jack-shaft 42 on which is also keyed a gear 43 of larger diameter than the gear 41. The shaft 42 is journalled between a pair of anti-friction bearings 44 and 45 in the change speed casing. The gear 43 in turn meshes with a smaller gear 46 rotatably mounted on roller bearing 47 on the shaft 15. When the clutch 35 engages the gear 30, the gear 46 rotates freely on the shaft 15. The face of the gear 46 opposite the gear 30 is provided with a toothed recess 48 which may receive teeth 49 on the clutch 35 on the opposite side of the shifting lever 36 from the teeth 34. When the clutch 35 is shifted to the left of teeth 33 the teeth 34 are unmeshed from the teeth of the gear 30 and upon further movement the teeth 49 engage the toothed recess 48 of the gear 46. The shaft 15 is then free to rotate relative to the gear 30 but is keyed to the gear 46 and is driven therefore through the speed multiplying mechanism of the gears 30, 41, 43 and 46.

The gear casing 14 may be of any suitable construction and is preferably provided with a closure plate 50 for the end of the shaft 42 and of sufficient size to permit the removal of this shaft and its bearings after removing the gears 42. This closure plate 50 is secured to a removable wall 51 of the casing which upon removal gives access to the entire interior of the casing. Access to the shifting rod 37 also can be obtained by means of other removable closures 52. The sprockets 16 and 20 may be formed integral with

the sprockets 17 and 18 respectively, and may be keyed to their respective shafts 15 and 19 in common with the respective sprocket wheels 17 and 18.

The above arrangement provides an independent rotary driving unit which may be operated independently of the usual drawworks hoist mechanism. The engine 10 may, therefore, be of a size suitable for driving the rotary and may, therefore, be efficiently operated. In drilling a "rat hole" the unit may be shifted as a whole to one side of the well being drilled without the necessity of re-aligning connecting parts with the draw-works. The engine may be reversed for unhooking, or other purposes, without interfering with the hoisting mechanism. The ability to operate the drill mechanism of the hoisting mechanism is also of advantage in certain operations, such as, fishing for broken tools where it is highly desirable to control the hoist and rotary with great accuracy and independent from each other. The provision of the coupling 40 and of the two sprocket wheels 16 and 20 also enables the rotary to be driven from the draw-works in emergencies such as a breakdown of the engine 10, particularly when the mid-Continental rig is employed, as in this case sprocket 20 may be aligned with the driving sprocket on the draw-works. In this case the rotary may be driven without effecting in any way the gear shift mechanism or associated parts.

In case the draw-works engine, or any parts associated with it, should break down the hoist may be driven in an emergency by connecting the sprocket wheel 16 to the calf wheel of the hoisting mechanism, whether the latter be arranged in the mid-Continental or California type of rigging. In this event the chain 39 may be removed and the shaft 15 uncoupled from the rotary so that the hoist may be operated without running the rotary. The change speed mechanism also enables the emergency hoisting mechanism to be operated at selected speeds best suited for the emergency. By having the change speed mechanism mounted directly on the engine or on its base, the necessity of a flexible coupling is avoided inasmuch as the change speed mechanism is in a unitary structure with the engine casing.

What we claim is:—

1. Well drilling apparatus comprising a base, a rotary and a reversible engine, both mounted on said base, a two speed transmission mounted between said engine and said rotary, a coupling between said two speed transmission and said rotary, a sprocket between said coupling and said two speed transmission and a sprocket between said coupling and said rotary.

2. Well drilling apparatus comprising a base, a rotary and a reversible engine, both mounted on said base, a two speed transmission between said engine and said rotary, a coupling, comprising a pair of coaxially arranged sprocket wheels and a chain having pins spanning said sprocket wheels between the teeth of said wheels, each of said coupling sprockets having a driving sprocket integral therewith.

3. Well drilling apparatus comprising a base, a rotary and a reversible engine, both mounted on said base, a two speed transmission mounted on said engine between said engine and said rotary, a coupling between said two speed transmission and said rotary, and a sprocket wheels, one between said coupling and

said two speed transmission and one between said coupling and said rotary.

4. Well drilling apparatus which comprises a base, a rotary and a reversible engine, both mounted on said base, a two speed transmission having a shaft aligned with the drive shaft of said engine, means to clutch said shaft to said engine directly and speed multiplying gearing through which said shaft may be coupled alternatively to the drive shaft of said engine, a coupling between said rotary and said shaft of said two speed transmission, a sprocket keyed on the shaft of said two speed transmission and a second sprocket keyed on the shaft of said rotary.
5. Well drilling apparatus which comprises a base, a reversible engine and a rotary both

mounted on said base, a two speed transmission between said engine and said rotary, a coupling between said rotary and said two speed transmission, and means for connecting said rotary to a second means for driving said rotary.

6. Well drilling apparatus which comprises a base, a rotary and a reversible engine both mounted on said base, a two speed transmission between said engine and said rotary, a coupling between said two speed transmission and said rotary, and means between said coupling and said two speed transmission for driving mechanisms from the latter.
